UNITED STATES PATENT OFFICE.

MASON EDWIN CLARK, OF SEATTLE, WASHINGTON.

WORK-HOLDER.

1,281,533.

Specification of Letters Patent. Patented June 26, 1917.

Application filed August 8, 1916. Serial No. 113,715.

To all whom it may concern:

Be it known that I, MASON EDWIN CLARK, a citizen of the United States, residing at Seattle, in the county of King and State 5 of Washington, have invented certain new and useful Improvements in Work-Holders, of which the following is a specification.

This invention relates to devices for clamping work upon the tables of drill 10 presses or other machines.

The object of my improvements is to provide a device of this character which is efficient in operation, and may be readily applied or detached from the work.

15 A further object is to afford self adjustable means which will accommodate itself to work having an uneven or irregular configuration to reliably hold the same in a predetermined position on the machine table.

20 The invention is of inexpensive and durable construction and will prove peculiarly advantageous in shops engaged in the manufacture of mechanical parts in quantities.

The invention is illustrated in the accompanying drawings, wherein Figure 1 is a plan view of the work holder shown applied upon a portion of a machine table. Fig. 2 is a side elevation of the device, with the supporting table shown in longitudinal section.

25 Fig. 3 is a transverse sectional view through 3—3 of Fig. 2. Fig. 4 is a detail view showing in side elevation the rear end of the device in inoperative condition. Fig. 5 is a view similar to Fig. 2, with the device represented as holding down work of a somewhat different character than that illustrated in the referred to view.

30 Figs. 6 and 7 are transverse sectional views taken through 6—6 and 7—7 of Fig. 5. Fig. 40 8 is a fragmentary view of one of the gripping bars to show the slot adjacent to the rear end thereof.

In carrying out the present invention, I provide a stand of a substantially U-shape 45 in transverse section consisting of a relatively large and flat base element 10 and two plate elements 11 extending upwardly from each side of the base element. Seated upon the latter, and between the side elements 11 50 of the stand is a cam 12 having a handle 13. Said cam is provided with a hole 15 through which extends the central portion of a pin 16, whose ends pass through vertically arranged guide slots 17 provided in the 55 stand elements. Provided on the eccentric, or the handle, as shown, is a laterally di-

rected lip or pawl element 18 for engaging in a suitably disposed notch of a rack 19 for securing the cam in a selected rotary position and it is thus maintained by a spring 20 acting against the side of the cam opposite to the rack. Said spring is furthermore provided with a stud 20¹ (Fig. 1) adapted to engage in a depression 21 of the cam when the cam is arrested by a stop 22 on the rack in the inoperative position in which it is shown in Fig. 4. 24 and 24¹ represent levers disposed at opposite sides of the aforesaid cam and a fulcrum post 25 which is secured to the machine table 26 in proximity 70 to the place whereat the work W is to be secured. The levers are connected with the cam by means of the pin 16 which extends through elongated holes, such as 27, Fig. 8, provided in the rear ends of the levers. 75

Said fulcrum post is detachably connected to the table 26 by providing a screw 28 on the post to extend through a selected table slot, as 29, to receive a securing nut 30.

The post is provided with a series of holes 31 to accommodate a fulcrum pin 32 as in Figs. 2 and 3, or a number of such pins as 32, 32¹ shown in Figs. 5 and 6. 80

33 represents a supplementary pin which may be employed in a hole of the fulcrum post to reinforce a subjacent fulcrum pin, as 32¹ Figs. 5 and 6, and for which end the pin 33 is provided at its outer end with a downwardly directed limb 33¹ which terminates in a concavity 33² adapted to seat upon 85 the associated pin 32¹.

The operation of the invention is as follows: The forward ends of the levers 24 and 24¹ are placed upon the work when the cam 12 is in its initial position illustrated in Fig. 4 and the pin 32 as in Fig. 2 is inserted in the hole 31 next above the levers where the top surface W¹ of the work which is to be engaged is level or substantially so. When the upper work surface is inclined from the 100 plane of the table or is in the nature of stops as W², W³, Figs. 5 and 6, two fulcrum pins may be utilized as in the referred to views. Being thus arranged, the operator actuates the cam 12 through the instrumentality of 105 its handle 13 to effect the elevation of the pivotal pin 16 to elevate the latter until the lever arms which are connected thereto are sufficiently raised to cause the other arms to bear down upon the work to clamp the same 110 to the table. As this occurs, the spring 20 asserts itself to push the arm lip 18 into en-

gagement with the notch of the rack with which it will register. In thus manipulating the cam, the operator may exercise a side pressure upon the handle in opposition to the 5 spring or he may allow the lip to progressively click in the various notches traversed.

The hole in the cam through which the pivotal pin extends is sufficiently large to enable the pin to be inclined as indicated in 10 Figs. 5 and 7 when required for clamping work of the character represented in these views. To enable the forward ends of the levers to be spread apart upon the work without inconveniencing the operator of the 15 device and to accommodate the tilting of the pin 16 which couples the levers to the cam, spacing collars 34 with convex ends 35 are provided on the pin 16 between the levers and the adjacent side elements 11 of the 20 stand.

What I claim as my invention is—

1. In a device of the character described, a pair of levers, a fulcrum post adapted to be fixedly secured to a work-table and provided with a plurality of holes, a fulcrum pin adapted to be inserted in a selected one of said holes, a stand consisting of a base and two spaced side elements, said side elements being furnished with guide slots, a 25 cam having its periphery seated on the base element of said stand, a pin extending through the cam and the two levers and being guided in the aforesaid cam slots, means to rotatably move the cam to actuate 30 said levers, and means to releasably secure the cam in clamping positions with respect to the levers.

2. In a device of the character described, a pair of work-clamping levers, a fulcrum 40 pin therefor, means adapted to be fixedly secured to a work table for holding said ful-

crum pin at selected elevations, a cam operatively connected to said levers, means to operate the cam for actuating the levers, a rack, and a pawl provided on the cam and 45 engageable in the rack for securing the cam in position to actuate the levers.

3. In a device of the character described, a pair of work-clamping levers, a fulcrum post having a series of holes, fulcrum pins 50 adapted to be employed in selected of said holes, a supplementary pin insertible in one of the post holes to reinforce one of the aforesaid pins at its outer end, and means whereby the levers may be influenced to 55 effect the clamping of the work in place.

4. In a device of the class described, a pair of levers, a fulcrum post disposed between the levers near their forward ends, a fulcrum pin engageable with said post at a 60 selected elevation, a cam disposed between the rear ends of the levers, and means for operatively connecting the cam to the levers whereby the latter afford independent vertical movements relative to each other.

5. In a device of the character described, a pair of clamping levers, an adjustable fulcrum serving for both of the levers, a stand, a cam connected with both of the levers for simultaneously operating the same, a rack, 70 a pawl element provided on the cam and engageable with the teeth of said rack, a spring tending to maintain the cam in position to engage said pawl, and means provided on the spring for yieldingly holding the cam 75 in inoperative position with respect to said levers.

Signed at Seattle, Washington, this 31st day of July, 1916.

M. EDWIN CLARK.

Witness:

E. PETERSON.
